CLAIM

The ornamental design for a convertible table, as shown and described.

DESCRIPTION

FIG. 1 is a top front isometric view of a first embodiment of a new, original and ornamental design for a convertible table, shown in a collapsed, table configuration.

FIG. 2 is a bottom rear isometric view thereof.

FIG. 3 is a front elevational view thereof.

FIG. 4 is a right side elevational view thereof.

FIG. 5 is a rear elevational view thereof.

FIG. 6 is a left side elevational view thereof.

FIG. 7 is a top plan view thereof.

FIG. 8 is a bottom plan view thereof.

FIG. 9 is a top front isometric view of the convertible table of FIG. 1, shown in an opened, stand configuration.

FIG. 10 is a bottom rear isometric view thereof.

FIG. 11 is a front elevational view thereof.

FIG. 12 is a right side elevational view thereof.

FIG. 13 is a rear elevational view thereof.

FIG. 14 is a left side elevational view thereof.

FIG. 15 is a top plan view thereof; and,

FIG. 16 is a bottom plan view thereof.
